UNITED STATES PATENT OFFICE.

CORNELIUS HOWARD O'ROURKE, OF HANFORD, CALIFORNIA.

FLYING-MACHINE.

1,277,467.

Specification of Letters Patent. Patented Sept. 3, 1918.

Application filed November 27, 1917. Serial No. 204,292.

To all whom it may concern:

Be it known that I, CORNELIUS HOWARD O'ROURKE, a citizen of the United States, residing at Hanford, in the county of Kings 5 and State of California, have invented new and useful Improvements in Flying-Machines, of which the following is a specification.

The present invention relates to improvements in flying machines, the object of the invention being to provide a flying machine which will have great stability, in which without materially increasing the resistance to its passage through the air, the aviator 15 can readily move from a position in front of the machine to a position behind the engine, or conversely, and which will have convenient means for operating the steering mechanism.

20 Other advantages of the invention will be hereinafter fully explained and particularly pointed out in the claim.

In the accompanying drawing, Figure 1 is a side view of the machine; Fig. 2 is a 25 plan view thereof, part being broken away to show the frame work of the machine; Fig. 3 is a front view; Fig. 4 is a longitudinal central vertical section on the line 4—4 of Fig. 2; Fig. 5 is a cross section on the line 30 5—5 of Fig. 2 looking to the front; Fig. 6 is a side view of the body of the machine, a propeller and other parts being removed; Fig. 7 is a cross section on the line 7—7 of Fig. 2, looking to the back; Fig. 8 is a cross 35 section on the line 8—8 of Fig. 2; Fig. 9 is a cross section on the line 9—9 of Fig. 2, looking to the rear.

Referring to the drawings, the frame of my improved machine comprises a plurality 40 of bars 1 extending longitudinally of the machine and spreading out at the center and connected at their front and rear ends. I have herein shown four only of these bars, but there may be any number as desired. 45 Surrounding said bars is a casing 2 of canvas painted, varnished, or the like, thus forming a chamber 3 for the engine 4, aviators or passengers, gasoline tank and other articles necessary to be carried. The chamber 50 3 is enlarged at the top, as shown as 7, by means of suitable longitudinal rods 8 and transverse rods 9, said enlargement having an opening at its front end through which an aviator on a seat 10 can observe the

direction of the machine and can steer it by 55 means of a steering wheel 11.

The shaft 12 of the engine extends forwardly and carries a propeller 13 at the front end of the air ship, while on the rear end of said shaft is secured to a sprocket 60 wheel 14 around which passes a sprocket chain 16 which also passes around sprocket wheels 17 on longitudinal shafts 18, supported as hereinafter described. Extending transversely, and suitably secured to the 65 frame of said casing, are supporting bars 19 which are connected by longitudinal bars 21 and form a frame for upper sustaining planes 22, said frames being covered with canvas, or like material. The frame of each 70 plane 22 also comprises bars 23 extending upwardly from the outside of the bottom of the chamber 3 and curving upwardly and outwardly in approximately parabolic curves and then horizontally and connected at their 75 outer ends with the upper transverse bars 19. The upper front sustaining planes 22 curve downwardly rearward, as clearly shown in Figs. 1 and 6, and, in addition, there is a lower sustaining plane 24 secured at its middle portion to the under side of the frame of the chamber 3, which lower plane likewise curves downwardly rearward. The lower plane 24 terminates in the same vertical plane as the upper planes 22, but its front 80 edge is very far to the rear of the front edges of the upper planes, also the downward curvature of said upper planes is much greater than that of the lower plane, so that 85 the air, guided against the rear portion of 90 said upper plane, exerts a strong lifting effect thereon. The air ship is supported partly by means of a pair of wheels 26 rotating loosely on a transverse shaft 27 which is supported by forwardly and rearwardly extending pairs of legs or braces 28 of which the front legs are secured to the frame of the chamber and the rear legs or braces are secured at their upper ends to the lower plane 24. Said legs 28 diverge downward so that 95 100 the wheels may be at a considerably greater distance from each other than the width of the body of the chamber 3.

Said lower plane is additionally secured to said upper plane by means of struts 29 and 105 ties 31 and supported upon certain of said struts 29 are bearings 32 for the propeller shafts 18. Propellers 33 mounted on said

2
shafts are at a proper elevation for propelling with the greatest possible effect the air passing rearwardly, having reference to the upper and lower sustaining planes of the 5 air ship.

Outside of said propellers the upper sustaining plane is cut away at its rear edge, as shown at 34, and in said cut-away portions are pivoted to the rear edges of the 10 upper plane, as shown at 36, ailerons 37, operated in a manner well known in the art by cords 38. Behind the engine is a second controlling seat 39, seated upon which an aviator can control a steering 15 wheel 41 which is connected to the same parts as the front steering wheel 11.

Pivoted to a transverse bar and depending therefrom are bars 42, the lower ends of which are suitably guided, and carrying 20 stirrups 44 by which they may be pushed forward by the aviator seated upon each of the seats 10 and 39. Said bars 42 are connected to cords 46 which are connected to the rudder 48 to steer the flying machine 25 to one side or the other. Connected to both bars 42 is a cord 49 which passes around a stationary pulley 51, so that, upon pushing one rod, the other rod is drawn to the steersman.

30 Secured to, and extending from, the rear portion of the frame of the chamber 3 are longitudinally extending bars 52, transverse bars 53 and curved outer bars 54 forming the frame work of a sustaining plane 56, 35 covered in the ordinary manner by canvas or other suitable material. The rear edge of said rear plane extends transversely of the air ship, and to said rear edge are pivoted, as shown at 57, elevating planes 58 40 extending rearwardly therefrom and operated in the usual manner. The inner edges of said elevating planes diverge from each other, and between them is located the steering rudder 48, its front edge being pivotally 45 secured to the rear edge of the frame of the chamber and also to the rear edge of a pin 59 extending centrally upward from said body. Cords extend from said steering rudder around direction pulleys 61 and 50 through holes in the body of the flying machine to the steering wheel, in the usual manner.

It is very important that provision be made for an aviator changing from one of 55 the two seats 10 and 39 to the other when required without unduly increasing the width of the body of the flying machine, said increase in width causing increased re-

sistance to the passage of the machine through the air. The difficulty of so passing from the observation seat in front of the engine to the controlling seat behind the engine is that of passing the engine. At present this is done by passing the engine on the same level as said engine. But 60 this requires that the body or chamber 3 be of sufficient width, not only to inclose the engine but also to provide a space on one side or the other, or both, of the engine along which a person can travel. Practically it is necessary that a space on both sides be provided, for it is necessary that both the engine and the chamber should be arranged symmetrically of the flying machine, and therefore it is not permissible to 65 provide a space only on one side of the engine. The resistance of the air to the passage of the flying machine being dependent principally upon the width of the body of the machine, and any increase in 70 its width increasing the resistance without correspondingly increasing the elevating or sustaining power, any increase in its width, therefore, is a dead loss to the flying machine. I overcome this objection by providing a passage directly over the engine, and for this purpose I provide transverse cleats or bars 62, and on the top of these are secured longitudinal bars 67, said bars 75 67 being spaced below the raised portion 7 90 of said chamber 3, so that an aviator can travel therebetween.

Additional chairs 68 for passengers are located behind the controlling chair 39.

For supporting the flying machine upon 95 the ground, there are provided, in addition to the wheels 26, a skid 69, pivoted at 71 to said body, the upper end of which is secured to one end of a spring 72, the other end of which is secured to the lower portion 100 of the body. The lower portion of the skid is adapted to contact with the ground as the machine travels.

I claim:—

An air ship having an engine for propelling the ship, aviators' seats before and behind the engine, a body inclosing the engine and the seats and of a width too narrow to permit the passage of an aviator therein by the side of the engine, the said body being sufficiently high to permit the passage of the aviator over the engine, and a support for the aviator permitting him to so pass over the engine. 105 110

CORNELIUS HOWARD O'ROURKE.
